UNITED STATES PATENT OFFICE.

WILLIAM G. ROUSSEAU, OF BALTIMORE, MARYLAND, ASSIGNOR OF ONE-HALF TO SAM W. PATTISON, WILLIAM H. GAHAN, AND LEWIS M. SPRAGUE, OF SAME PLACE.

DESIGN FOR A HOOK.

SPECIFICATION forming part of Design No. 32,986, dated July 24, 1900.

Application filed May 23, 1900. Serial No. 17,763. Term of patent 14 years.

To all whom it may concern:

Be it known that I, WILLIAM G. ROUSSEAU, a citizen of the United States, residing at Baltimore city, in the State of Maryland, have invented and produced a new and original Design for Hooks, of which the following is a specification.

This design relates to a novel and ornamental form of hook, reference being had to the accompanying drawing, in which the figure is a perspective view of the hook embodying the distinctive features of my design.

As shown in said figure, the design consists of a hook having two vertical rods or parts c c' , spaced apart and separated from each other throughout their length and merging at their lower ends into reverse curves b , which are also spaced apart and separated from each other. Emanating and projecting upwardly from said curves b are straight prongs a and a' , approximately parallel with the rods c and c' , respectively, and also spaced apart and separated from each other throughout their

length, which is the same as or approximating the length of the said rods. The upper ends of the said rods c and c' merge into reverse curves d , which are spaced apart and separated from each other, and emanating and projecting downwardly from said curves d are parallel straight parts e e' , which are spaced apart and separated from each other and are united at the bottom by a curve f , said two downwardly-projecting parallel parts e and e' and their uniting-curve f extending as low down as the curves b .

Having thus described my invention, what I claim is—

The design for a hook substantially as herein shown and described.

In testimony whereof I affix my signature in the presence of two witnesses.

WILLIAM G. ROUSSEAU.
